CLAIM

The ornamental design for an autonomous vehicle control button, as shown and described.

DESCRIPTION

The present application is also related to application Ser. No. 29/491,937, entitled Autonomous Vehicle Overall Interior; to application Ser. No. 29/578,541, entitled Autonomous Vehicle Overall Interior; to application Ser. No. 29/491,870, entitled Autonomous Vehicle Storage Bin/Tray; to application Ser. No. 29/491,867, entitled Autonomous Vehicle Console; to application Ser. No. 29/491,868, entitled Autonomous Vehicle Seat; to application Ser. No. 29/547,496, entitled Autonomous Vehicle Seat; to application Ser. No. 29/491,889, entitled Autonomous Vehicle Go/Pull Over Button; and to application Ser. No. 29/578,534, entitled Autonomous Vehicle Go Button, the entire disclosures of which are incorporated by reference herein.

FIG. 1 is a top view of an autonomous vehicle control button according to a first embodiment; and,

FIG. 2 is a top view of an autonomous vehicle control button according to a second embodiment.

As shown by the figures, the buttons are planar. Areas of the design shown with a stipple fill have an appearance that contrasts with the non-stipple filled areas. The specific font used is exemplary, and is not intended to limit the design to any particular font style or size thereof.
